UNITED STATES PATENT OFFICE.

AUGUSTUS JOHN MARQUAND, OF CARDIFF, COUNTY OF GLAMORGAN,
ENGLAND.

ELECTRICAL APPARATUS FOR PREVENTING CORROSION OF STEAM-BOILERS.

SPECIFICATION forming part of Letters Patent No. 393,072, dated November 20, 1888.

Application filed January 17, 1888. Serial No. 261,057. (No model.) Patented in England June 10, 1887, No. 8,396.

To all whom it may concern:

Be it known that I, AUGUSTUS JOHN MARQUAND, a subject of the Queen of Great Britain, and residing at Bute Docks, Cardiff, in the county of Glamorgan, England, engineer, have invented certain new and useful Improvements in Electrical Apparatus for Preventing Corrosion or Incrustation of Steam-Boilers and other Similar Vessels and for Removing the Incrustation when Once Formed, (for which I have obtained a patent in Great Britain, No. 8,396, bearing date June 10, 1887,) of which the following is a specification.

My invention relates to an improved apparatus for applying electricity to steam-boilers and other similar vessels for the purposes of preventing the formation of incrustation, of removing it if already formed, and also of preventing corrosion or pitting of the internal surfaces.

According to my invention the terminal of an electric generator corresponding with the zinc plate of a battery is electrically connected in any convenient way, and either directly or indirectly with the shell, while the terminal corresponding with the carbon or iron of the battery is connected to the conductor, which latter is passed through the shell into the water-space, but is electrically insulated from the shell. This method will therefore make the internal surfaces negative and the insulated conductor positive. I have found, as a matter of fact, that if the current flows in a direction the reverse of the one above described local action on or corrosion of the inner surfaces of the shell will be increased, but that if the electricity be applied according to my present invention corrosion cannot and does not take place; and, as it is generally believed that my method of applying an electrical current to a boiler will not prevent incrustation, I wish it to be distinctly understood that experience with my invention proves that incrustation already formed will be removed by it and its readherence effectually prevented.

Figure 1 is a detail sectional elevation illustrating the construction of my improved apparatus and its connection to the boiler-shell. Fig. 2 is an elevation illustrating the application of my invention to a marine boiler. Fig. 3 is a diagram elevation illustrating the appli-

cation of my invention to a land boiler. Fig. 4 is a detail.

Referring to Fig. 1, A is the shell of the boiler, electrically connected to the negative pole of the battery. B is the conductor. This may be a metal knob; but I prefer to use a perforated box of any convenient section, which is filled with zinc. C is a ferrule screwed into the boiler-shell, and D is an efficient insulation fixed inside the ferrule and covering both ends of it by means of flanges or washers d d'. E is a stud, to the end of which the conductor is securely attached in any convenient way. The stud is passed through the ferrule, from which both it and the conductor are, however, insulated, as shown. A nut, e, on the outer and screwed end of the stud is provided for the purpose of fixing the conductor firmly in its position. F is the lead from the positive pole of the battery coupled to the outer end of the stud E. G is a cap having a perforation, f, (through which the positive lead is taken,) adapted to screw onto the ferrule for the purpose of protecting those parts of the apparatus which it covers from being injured.

Referring to Fig. 2, H is a marine boiler, and B the conductor, constructed as described above. I is the battery, carried by a metal bracket, i, which is bolted to the boiler-shell. K is the lead from the negative pole of the battery to the metal plate i, by which the boiler-shell is electrically connected to the said pole. L is the lead from the positive pole of the battery to the conductor B.

Fig. 3 is a diagram illustrating the above-described single-lead method of applying my invention to a land boiler. M is a pipe connected to the boiler, and m a clip suspended therefrom. The battery I is carried by the clip m, and the negative pole is electrically connected to the clip m and through it to the boiler shell N by the lead n. L is the lead from the positive pole of the battery to the conductor B. O is an indicator introduced into the circuit anywhere along the lead L.

I do not confine myself to any particular type of indicator, but may use any that is capable of indicating the existence of an electrical current as well as the direction in which it is flowing.

A modified and preferable method of con-

necting the negative pole of the battery with the boiler-shell is illustrated in Fig. 4, which illustrates a battery adapted to be suspended from a pipe attached to the boiler in the same way as illustrated in Fig. 3, described therewith.

Instead of using a wire lead, *n*, from the negative pole *N'* to the clip *m*, I use a metal strip, *s*. This modification may also be introduced into an apparatus constructed as described with reference to Fig. 2. The advantage of the said modification is that only one wire lead between the battery and the boiler is required.

I do not confine myself to the number of batteries, circuits, or conductors I make use of, inasmuch as these may be varied according to convenience. If more than one apparatus be used on one boiler, they may be coupled up in series, if preferred.

I claim—

1. The combination of boiler-shell, metal bracket riveted thereto, and a battery carried thereby, the negative pole of which is electrically connected direct to said bracket,

an electrical conductor fixed to the boiler-shell, insulated therefrom, and in electrical contact with the water in the said boiler, and a wire lead from the positive pole to the said conductor, as set forth.

2. The combination of boiler-shell, metal clip adapted to support a battery and to be suspended from a pipe leading from the boiler, the negative pole of the said battery being connected direct to the said clip, an electrical conductor fixed to the boiler-shell, insulated therefrom, and in electrical contact with the water in the said boiler, and a wire lead from the positive pole to said conductor, as set forth.

In witness whereof I have hereunto set my hand this 21st day of November, 1887.

AUGUSTUS JOHN MARQUAND.
